APPARATUS FOR GRINDING CORRUGATED ROLLS AND BEDPLATES

Filed March 23, 1926

UNITED STATES PATENT OFFICE.

ROBERT B. JONES, OF BARRE, VERMONT, ASSIGNOR TO JONES BROTHERS COMPANY,
OF BOSTON, MASSACHUSETTS, A CORPORATION OF MAINE.

APPARATUS FOR GRINDING CORRUGATED ROLLS AND BEDPLATES.

Application filed March 23, 1926. Serial No. 96,895.

This invention relates to a method and apparatus for grinding two corrugated surfaces to form mutually interfitting complementary engagement with each other.

5 In the grinding of soft or yielding materials, the dimensions of clearance or free path between opposed grinding surfaces is substantially the determinative factor in the degree of disruption and comminution to which 10 the material may be reduced in a given apparatus. In devices intended for handling this type of material the continued movement of the material over or between the grinding surfaces is directly dependent upon the frictional rubbing and sliding action therebetween. However, such surfaces will not continue to grind or comminute such substances if separated a sufficient distance to permit the 15 free flow of the material between them.

20 In the art of grinding and pulverizing chocolate, for example, it is common practice to employ a stone bed-plate, which may be flat or trough-shaped, and a cylindrical stone roll resting thereon. The roll is pushed or 25 rolled backward and forward upon the bed-plate,—the chocolate being caught, crushed and ground between the two surfaces by the relative rolling or sliding movement of the roll. For this purpose, it is obviously desirable 30 that the opposed surfaces shall present as great an area as practicable. To this end it is usual to provide corrugations upon the roll which preferably stand perpendicular to the axis and which are adapted to fit into 35 corresponding longitudinal corrugations or grooves provided upon the bed-plate. This arrangement introduces an additionally effective malaxating action upon the chocolate as successive portions of the corrugations on 40 the wheel enter and leave the corrugations on the bed-plate. However, it will be clear that if irregular projections occur upon either surface, they will be gradually removed by the rolling action and thus contaminate the 45 chocolate produced. Again, if there are depressions of appreciable depth or area they will accumulate chocolate and the apparatus will cease to function in such spots.

Hence, it is an object of the present invention to provide a method and apparatus for 50 making a corrugated bed-plate and one or more corrugated rolls corresponding thereto

which shall mutually interfit to form complementary engagement therebetween and substantially exactly coincide throughout their 55 relative paths of traverse movement when employed in the subsequent grinding or milling operations for which they are intended. Other objects will appear from the following disclosure.

In general, the method of the invention comprises the preliminary fashioning of a flat stone bed-plate and one or more rolls from stone of substantially the same degree of hardness and cutting parallel longitudinal corrugations in the surface of the bed-plate and corresponding annular corrugations upon the roll or rolls, with such degree of accuracy as may be practicable. The thus corrugated rolls are then positively rotated 60 about their respective geometric axes, and while being thus driven are brought into registry with the corrugations on the bed-plate, both sets of corrugations loosely interfitting or meshing with each other. The rolls 65 and bed-plate are then subjected to relative longitudinal reciprocatory movement throughout the length of the corrugations upon the bed plate. The roll or rolls are held in constant but light contact with the bed-plate. This path or traverse is preferably 70 equal to or greater than that subsequently involved in the relative traverse movement to be employed in the pulverizing operations. Preferably the paths traversed by adjacent rolls (running in tandem) upon the 75 bed-plate will overlap.

The apparatus of the invention will be described from the illustration of a preferred embodiment shown in the accompanying 80 drawings, in which:—

Fig. 1 is a side elevation of the grinding machine; and

Fig. 2 is an end elevation of the grinding machine parts being broken away to show 85 the middle roll, as mounted for use in pulverizing operations.

Referring to Fig. 1, the grinding machine includes a truck 1 which is mounted to run upon a pair of rails 2 and adapted to carry 100 the bed-plate 3 in a horizontal position.

The rails 2 are fixed to sleepers and heavy wooden floor beams 4 which extend laterally of the rails and serve to receive brackets 5.

Beams 6, parallel to the floor beams 4 and fixed at a suitable height thereabove to allow sufficient clearance, are also fitted with brackets 7. Ways or guides 8 are positioned and firmly held in vertical position between the brackets 5 and brackets 7, respectively, on either side of the track 2. Beams 6 are held in spaced relationship by reinforcing rods 9.

The roll carrier 10 is suspended between the vertical uprights 8 by means of straps 11, 11' attached thereto on either side and to a cross bar 20 at the top. The carrier may be raised and lowered by any suitable means as for example by the means shown in my prior Patent No. 1,290,224 dated January 7, 1919. Since the particular means to be employed forms no part of the present invention, it is not set forth in the drawings. At the corners of the carrier 10 sleeves 12 are provided which slidably receive the vertical uprights 8 passing therethrough and restrain the carrier to an accurate up and down movement only.

Angle irons 13, 13' by which the sleeves 12 are carried support upstanding plates 14, 14' upon which is mounted in suitable bearings a horizontal axis 16 having loose and driving pulleys 17 and at one end, a gear wheel 18. The gear wheel 18 meshes with an intermediate gear wheel 19 mounted in the plate 14.

In horizontal alignment upon angle iron 13, there are provided three intermeshing gears 21, 22, 23 turning upon axles 21', 22', 23', mounted in suitable bearings thereon each axle having a concentric hub at its inner end. Corresponding bearings, axles and hubs are supported on the angle iron 13'. Cylindrical stone rolls to be ground are now mounted by any suitable means of engagement upon the hubs between the pairs of opposed bearings thus arranged. In Fig. 2 is shown a hub 22" on the axle 22' and a co-operating hub 25 between which hubs is supported a roll 27. The bed plate 3 and rolls 27 are provided with suitably spaced corrugations, as stated above, by cutting or by other suitable means. Such corrugations are substantially correct but in order that the rolls and bed plate function properly, they must mutually interfit and coincide substantially exactly. This finished condition is preferably attained in the following manner.

The bed plate 3 is horizontally positioned upon the truck 1 with the corrugations thereon parallel to the rails upon which the truck is mounted, and then further adjusted laterally so that the corrugations of the bed plate stand directly under the corrugations upon the rolls and in interfitting relationship therewith.

A fluid grinding mixture (usually of water emulsion and a pulverized granular abrasive) is spread over the surface of the bed plate. The carrier is then lowered until the

rolls come into contact with the bed-plate, preferably with light pressure contact at the start. The driving pulley 17 is then connected (as by a belt, not shown) to a suitable source of power whereupon the gear 18 is revolved and drives through more slowly, the intermediate gear 19 which in turn acts directly upon the gear 22. For a given direction of rotation of gear 22, as indicated by the arrow, the gears 21 and 23 which are meshed therewith are both driven in the direction opposite to that of the gear 22. Accordingly, the rolls 27 are rotatably driven in a corresponding manner against the opposed surface of the bed-plate 3 lying thereunder.

The initial grinding action between the two corrugated surfaces, as already noted, must usually be done with light contact unless in the preliminary preparation of the stones substantially exact registry has been effected, which is not usually the case and ordinarily not commercially feasible. If this precaution is not observed, chipping may occur and local overheating is almost certain to result. By maintaining light pressure contact, however, these difficulties may be effectively avoided.

After proper adjustment of the rotating rolls and of the bed-plate has been satisfactorily accomplished the bed-plate is slowly advanced longitudinally by pushing the truck upon which it is carried along the rails 2. This movement also should be initiated slowly and without appreciable pressure until after a few passes have been completed, extending throughout the desired length of traverse.

The grinding action thus set up is continued, until the corrugated surfaces of the roll or rolls and of the bed-plate are substantially complementary each to each throughout their entire lengths and are provided with finished surfaces which are sufficiently smooth.

When a plurality of corrugated rolls are being ground to fit a single bed-plate each traverse of each roll with respect to the bed-plate, should overlap that of the roll or rolls ahead or behind it.

The total traverse of the rolls may stop short of the ends of the bed-plate, or may extend throughout its entire length. When the full length of the bed-plate is thus ground two or more may be assembled end to end in abutted relationship in the construction of them for the pulverizing operations. Ordinarily it is preferable not to construct a mill in which the rolls pass over a jointed seam, since the corners, though in close abutment and firmly joined are subjected to cracking or splitting under compression.

It is clear that various modifications and adaptations of the invention may be made in actual practice, without departing from the

scope of the above disclosure, but such modifications and adaptations are to be considered as comprehended by the present specification and included by the following claims.

5 I claim:

1. A machine for finishing the contour of annular corrugations in a series of rolls and of longitudinal corrugations in a bed-plate so that the corrugations of the rolls and of the bed plate will mutually interfit and substantially coincide comprising a longitudinally movable support for the bed-plate and a carrier for the rolls, intermeshing gears mounted at the ends of the rolls and means on said carrier for rotating the rolls independently of the plate whereby as the plate support is caused to reciprocate longitudinally the corrugations of each roll will follow the corrugations of the adjacent roll and 20 coact in turn with the corrugations of the bed plate.

2. A machine for finishing the contour of annular corrugations in a series of rolls and of longitudinal corrugations in a bed-plate so that the corrugations of the rolls and of the bed plate will mutually interfit and substantially coincide comprising a longitudinally movable support for the bed-plate and a carrier for the rolls, intermeshing gears mounted at the ends of the rolls and means 25 on said carrier for rotating the rolls independently of the plate, each roll being driven in a direction opposite to that of an adjacent roll whereby as the plate support is caused to reciprocate longitudinally the corrugations of each roll will follow the corrugations of the adjacent roll while being rotated in the opposite direction and coact in turn with the corrugations of the bed-plate.

Signed by me at Barre, Vermont, this 17th 40 day of March, 1926.

ROBERT B. JONES.
